Primary Examiner — Rhea Shields(74) Attorney, Agent, or Firm — Ostrolenk Faber LLP(57) CLAIM

The ornamental design for a handle for a personal care appliance, as shown and described.

DESCRIPTION

1.1 is a front view illustration of a handle for a personal care appliance, according to our new design;

1.2 is a top view illustration thereof;

1.3 is a right side view illustration thereof;

1.4 is a left side view illustration thereof;

1.5 is a front, bottom, left side perspective view;

1.6 is a front, top, right side perspective view illustration thereof; and,

1.7 is a rear view illustration thereof.

In the drawings, the broken lines are for the purpose of illustrating environment only and form no part of the claimed design.
